UNITED STATES PATENT OFFICE

2,426,750

BOTTLE CARRIER

Emil A. Reutner, St. Louis, Mo.

Application March 10, 1945, Serial No. 582,000

6 Claims. (Cl. 224—45)

1

This invention relates generally to a bottle carrier, and more particularly to a device whereby bottles may be carried away by purchasers of the same, in a simple, inexpensive and efficient manner.

The invention has among its objects the production of such a bottle carrier that will be extremely easy to make and use, rapidly applied to and removed from the bottles as required, of minimum size so as not to be cumbersome in use, and otherwise satisfactory and efficient for use wherever deemed applicable.

One of the principal objects of this invention is to so construct a device of the kind described, that it will be made of but a single piece of material, will have no cooperating parts likely to get out of order, and yet be perfectly suited for the intended function of temporary carriage of bottled goods.

Another object of my invention is to provide a carrier for bottled goods, that will permit of the latter to be inserted through an opening in the carrier and thence shifted away from the point of entry, so as to be carried by the neck of the bottle in engagement with the carrier.

A further object of this invention is to so construct devices of the kind aforesaid, in such a manner and shape that they may be superimposed vertically on one another, for storage and shipment, and will occupy the least amount of space while stored or in transit.

An added object of my invention is to so shape the said carrier that a considerable substantially flat surface is provided thereon, for the imprinting, embossing or otherwise applied advertising matter thereon, if desired.

A still further object of this invention is to provide a device of the kind described, wherein there will be an elongated opening through the carrier, this opening being sufficiently enlarged at a point of its length to permit of the capped end of a bottle to be inserted therethrough, said bottled goods then shifted along the opening and away from said enlarged portion, so as to be suspended by its neck when the carrier member is lifted.

Another added object of my invention is to so construct the elongated opening in the carrier element, that it will be at least long enough to permit of insertion of one or more fingers of the carrying hand therethrough, after the bottle or bottles have been operably inserted into the opening, and whereby said fingers act to provide stops against accidental displacement of the bottles from the opening during transportation.

2

Many other objects and advantages of the construction herein shown and described, and the uses mentioned, will be obvious to those skilled in the art to which this invention appertains, as will be more clearly apparent from the disclosures hereinafter given.

To this end, my invention consists in the novel construction, arrangement and combination of parts, as herein shown and described and as will be more clearly pointed out in the claims hereunto appended.

In the drawings, wherein like reference characters represent like or corresponding parts throughout the views,

Figure 1 is a plan view of the device;

Figure 2 is a cross-sectional view, taken substantially along the line 2—2 of Fig. 1; and

Figure 3 is a perspective view of the carrier in use.

Referring more particularly to the drawings, wherein I have illustrated a preferred embodiment of my invention, there is shown a one-piece member 1, stamped or otherwise formed out of plastic, wood, paperboard, metal, etc., as desired so long as the sheet will be sufficiently rigid and sturdy to substantially retain its shape while carried with the load therein.

This sheet is provided with one or more openings or slots 2—2 therethrough, there being a pair of such openings in the present instance, extending longitudinally of the sheet and spaced apart throughout their length.

Each slot is provided with an enlargement 3 at some point of its length, to permit of the capped end of a bottle to be extended therethrough, while the remaining length of the slot is reduced in width to approximately the diameter of the bottle neck slightly below said cap. Thus, the bottles may be successively threaded with their capped ends uppermost, through the said enlargements and then shifted transversely so shifted will be suspended at their necks in said reduced portions of the slots when the carrier member is lifted for service.

The slots 2—2 are preferably slightly longer than the space occupied by the bottles as carried therein, and preferably terminate adjacent one end of the carrier member, so that in carrying the loaded member, the fingers of the carrying hand may be inserted through the uppermost ends of the slots, and will serve effectively as limit stops against longitudinal movement in that direction, of the bottles so carried.

In addition, and to facilitate comfortable car-

rying of the device, an opening 4 is made through the sheet, intermediate of the pair of elongated openings 2-2 and independent thereof, but slightly below the uppermost closed ends of said pair of slots, so that when it is desired to carry the device, different fingers of the carrying hand are inserted through the several openings, from one face of the sheet, while the thumb engages the sheet on the opposite face, thus straddling the uppermost end of the carrying member.

The bottles thus carried as aforesaid will shift themselves so that their longitudinal axes are substantially vertical, but they will not drop out of the carrier, inasmuch as they will engage the reduced portions of the slots at the bottle necks, and the top beads or enlargements of the bottles thereabove, and the caps themselves, will absolutely prevent the bottles passing freely downwardly except at the enlarged opening points 3, and even then, the fingers must be withdrawn from carrying position to permit of the bottles being manually unthreaded from the carrier.

Having thus described my invention, it is obvious that I do not wish to be limited to the exact form, arrangement, construction and combination of parts herein shown and described, except as limited by the prior art, and the claims hereunto appended.

What I claim as new and desire to secure by Letters Patent is:

1. A bottle carrier comprising a substantially flat rigid sheet having an elongated opening to permit passage of the capped end of a bottle therethrough and reduced in size away from said enlarged portion, to suspend a bottle from said reduced portion of the opening, said opening being long enough to permit passing the fingers through the same after said bottle has been so suspended to carry the device and act as a bottle-engageable stop to prevent movement of the bottle in the carrier while in carrying use.

2. A bottle carrier comprising a substantially one-piece rigid sheet of material having an elongated opening enlarged at one point of its length to permit passage of the capped end of a bottle therethrough and reduced at other portions of its length to suspend the bottle by its neck in said opening, said opening being sufficiently elongated to permit the thumb and fingers of the hand engaging on opposite sides of said sheet with the fingers passing through said opening to provide a bottle-engageable stop against movement in one sliding direction of the carried bottle while carrying the device.

3. A one-piece bottle carrier comprising a supporting sheet having an elongated opening sufficiently enlarged at one point to permit passage of the capped end of a bottle therethrough, and reduced in width away from said enlargement so that the bottle may be shifted along said opening and away from said enlargement to suspend the bottle by the neck in the reduced portion of the opening, said opening terminating adjacent one end of the sheet to permit of grasp-

ing at that end by insertion of the fingers of a hand through said opening thereat for carrying with a bottle suspended in the opening.

4. A substantially flat sheet having an elongated opening with an enlarged portion to permit free passage of the capped end of a bottle therethrough and sliding of the bottle along said opening and away from said enlargement to suspend the bottle by its neck, and another opening through said sheet and spaced from the first opening to permit insertion of different fingers through both openings together when carrying said sheet with a bottle suspended in the first opening.

5. In a device of the kind described, a relatively rigid sheet having a pair of spaced apart longitudinally extending openings each enlarged at one point to permit passage of capped bottles in sequence therethrough and each opening reduced in width away from said enlargement so that when the bottles are shifted away from said point of entry after passage through said enlargement, they will be suspended at the reduced portions of the openings, both of said openings terminating sufficiently closely adjacent one end of the sheet, to permit the fingers to be inserted through said openings from one face of the sheet and the thumb overlie the opposite face of the sheet to carry the device.

6. In a bottle carrier, a one-piece member made of a rigid sheet provided with a pair of elongated openings each having an enlargement at one end of the sheet to permit passage of the capped end of bottles therethrough and reduced in width away from said enlargement so that said bottles may be shifted in sequence away from said enlargements after being passed through the latter, and another opening through said sheet intermediate said pair of openings adjacent said enlargements, and whereby the device having the bottles suspended therein may be carried by using the hand to straddle said end of the sheet with fingers through the pair of elongated openings to form a stop against displacement of the bottles through said enlargements, with another finger through said intermediate opening, and with the thumb arranged at the opposite side of said sheet.
